PAUL HOFFMAN, OF LA GRANGE, ILLINOIS, AND JAMES B. STRONG, OF SUFFERN, NEW YORK, ASSIGNORS TO RAMAPO AJAX CORPORATION, OF NEW YORK, N. Y., A CORPORATION OF NEW YORK.

SAFETY LOCKING DEVICE.

Application filed November 27, 1926. Serial No. 151,047.

This invention relates to locking devices for switchstands, and more particularly to a safety locking device for holding the locking members of such locking device in locked position even though the switchstand is destroyed.

In a well known type of switchstand construction the switchstand having the mechanism for operating the switch points is spaced from a separate locking device for holding the switch points in adjusted position. Besides the separate locking device the switchstand may also have a lock incorporated therewith, thereby providing two locks or a so called double locking switchstand. This construction has proven very satisfactory under most conditions of operation. However, if the switchstand be destroyed or displaced bodily, it may happen that this displacement will unlock the separate locking device.

According to the invention the possibility of the separate locking device accidentally becoming unlocked is eliminated by providing the separate locking device with a safety device which positively prevents accidental unlocking of the separate locking device. A fragile connection between the separate locking device and switchstand may also be provided which will break whenever it is subjected to a stress greater than the usual working stress.

Various other features and advantages of the invention will be obvious from the following particular description of one form of a device embodying the invention, or from an inspection of the accompanying drawings; and the invention also consists in certain new and novel features of construction and combinations of parts hereinafter set forth and claimed.

In the drawings accompanying and forming part of this specification, a practical commercial embodiment of the invention is disclosed, but as such illustration is primarily for purposes of disclosure, it will be understood that the structure may be modified in various respects without departure from the broad spirit and scope of the invention as hereinafter defined and claimed.

In the drawings:

Fig. 1 is a perspective of the safety locking device according to the invention;

Fig. 2 is a plan view of the switch points,

switch stand and safety locking device with connecting elements;

Fig. 3 is an elevation of the switch stand and safety locking device showing the latch in cocked position ready for dropping into locking position when the locking pin is moved to locking position;

Fig. 4 shows the latch after it has dropped to locking position; and

Fig. 5 is a detail showing the construction of part of the switch stand.

In the following description and in the claims parts will be identified by specific names for convenience, but they are intended to be as generic in this application to similar parts as the art will permit.

Referring now to the drawing, the thru rails are denoted by A and B and the switch points are denoted by 1 and 2. Above the switch the thru rails A and B act as the main rails, while below the switch the main rails may be thru rail A and the rail of which switch point 2 is a part. In this case the branch rails will be thru rail B and the rail of which switch point 1 is a part. It will be understood that the switch is of usual construction and by itself forms no part of the present invention. These switch points 1 and 2 are connected together by means of tie rods 3 and 4 and are connected to the switch stand and safety locking device, as explained hereinafter more in detail.

The switch stand 6 which may be of standard construction as illustrated in Figs. 3 and 4 comprises a body or casing 7 having a base 8 which may be secured to two of the cross ties 9. The casing 7 has a spindle 10 with a crank arm 11 having suitable connection to the tie rod 4, including a connecting rod 12 for throwing the switch points 1 and 2 from one position to the other. Rigidly mounted on spindle 10 is a squared sleeve 14 with a bracket 16 to which is pivoted a handle 17. Slidably mounted on the sleeve is a locking block 13 having an annular collar 15, and a downwardly projecting square portion 22 which fits neatly into a square opening in top of body or casing 7. The handle is bifurcated at its upper end, the two members straddling the bracket 16 and the locking block 13, and having curved portions 18 disposed between projecting lugs 19 on respective sides of the locking block 13. The handle 17 may have a suitable opening for

receiving a projection 20 on the locking block 13, and having a hole 21 in the end thereof through which a padlock (not shown) may be passed to lock the handle in position to prevent movement thereof. The connection between the handle member and the locking block is such that by raising the handle member, the locking block may be raised on the spindle to the position shown in Fig. 3, thus disengaging the square portion 22 of the locking block from the body or casing, and allowing the handle, locking block and spindle to rotate and throw the switch.

15 At the side of the switch stand body 7 may be a locking rod 23 guided by a guide member 25 and having a forked head 26 (see Fig. 5) embracing the annular collar 15. The lower end of the locking rod 23 is connected to a bell crank lever 27 pivoted to the switch stand body, the lower end of which lever has operative connection to the safety locking device as hereinafter described more in detail. It will be seen that, 20 as the handle 17 is raised or lowered, the locking block 13 will cause the locking rod 23 to move along with it.

25 The improved safety locking device may comprise a base 30 having disposed at one side thereof a lock block 31 having a chamber in which may be disposed a bar 33 having operative connection with the switch points by suitable means including a connecting rod 34. The block 31 has a transverse hole 35 extending therethrough, and the bar 33 has a plurality of holes 36 to register with the transverse hole 35 selectively, according to whether the switch points are in one position or the other.

30 The base 30 may further be provided with an upstanding latch block 38 having a chamber in which may be disposed a cross bar 39 having secured at one end a pin 40 for disposition in the transverse opening 35 and the 35 openings 36 in the bar 33. A cross head 41 may be provided rigidly secured to the cross bar 39 and having a connecting rod 42 pivotally connected thereto. The other end of the connecting rod 42 is connected to the bell crank lever 27. This connecting rod 42 may be drilled at points 43 throughout its length to so weaken the bar that it will break when subjected to a predetermined minimum abnormal stress, the operation being explained more in detail hereinafter.

35 To the upper end of the latch block 38 which is forked the latch 45 is pivoted, the latch having upper and lower tripping projections 46 and 47 respectively. The latch 40 may have a groove 48 in its lower edge providing ears to straddle cross bar 39, thereby to insure the positive positioning of the latch between the cross head 41 and the latch block 38.

45 When the switch points are in one of their

operating positions, as shown in Fig. 2, the handle member 17 will be in the position shown in Fig. 4 and the pin 40 will be in locked position, the latch 45 being in the position shown in Fig. 4 positively preventing the return of the pin 40 from its locked position. The switch points are locked both by the square portion 22 of the locking block 13 engaging the square opening in top of body or casing 7, and the pin 75 40 being in locking position, these two conditions being brought about simultaneously by the lowering of the handle member 17. It will be appreciated that, even tho the switch stand be knocked over, as for instance by something overhanging on a freight car, the bodily movement of the switch stand cannot pull the pin 40 from its locked position because of the inter-position of the latch 45. Furthermore, due to 80 the breakable connection, the connecting rod 42 will easily be broken and the switch stand may be carried any distance without interfering with the positive safety lock on the switch points, thereby insuring the switch 85 points remaining in their original operative position.

90 When it is desired to throw the switch points to another position, the latch 45 is tripped manually or by the operator extending his toe under the tripping projection 46 and tripping the latch to the position as shown in Fig. 1. The handle 17 may be raised to the position shown in Fig. 3 and the spindle 10 rotated until the switch 95 points are in their other position. The raising of the handle 17 withdraws the lock pin 40 from its locking position, and, as the cross bar 39 moves under the latch 45, the tripping projection 47 is engaged by the cross 100 bar 39 to cause the latch 45 to fall down upon the cross head so that the parts assume the position shown in Fig. 3, the latch 45 being in cocked position and in readiness to drop by gravity to locking position as soon as the 105 pin 40 is placed in locking position.

110 Thus the safety device is made fool-proof in that it is impossible for the operator to forget to place the latch in cocked position because the relation of the parts automatically puts the latch in cocked position whenever the pin 40 is withdrawn to unlocked position.

115 Thus a double locking switch stand is provided, one of the locks having a safety latch 120 which will hold the switch points in their thrown position irrespective of damage to or destruction of the switch stand. The latch must be manually disengaged but, when once tripped the relation of the parts 125 insures that the latch will be automatically placed in cocked position for automatically locking itself. Thus the construction is fool-proof and provides a positive assurance 130 against the switch points being accidentally

thrown due to destruction of or damage to the switch stand.

While certain novel features of the invention have been shown and described and have been pointed out in the annexed claims, it will be understood that various omissions, substitutions and changes in the forms and details of the device illustrated and in its operation may be made by those skilled in the art without departing from the spirit of the invention.

Having described our invention, we claim:

1. In combination with a switch stand, a safety lock device comprising a base, locking members on said base for holding a switch in operative position, one of said locking members having an abutment, a latch member pivoted on said base and adapted to engage said abutment to lock said locking members in locked position, said latch member having a projection to be engaged by one of said locking members when it is moved to unlocked position, said engagement tripping said latch member to position resting on said abutment, so that, when said abutment is moved to locked position, said latch member will move to locked position.

2. In combination, a switch stand having means for operating a switch, a lock device having lock members for holding said switch in operative position, a safety device on said lock device for positively holding said lock members in locked position, connections for operating said auxiliary lock device from said switch stand including a fragile member which will break whenever the stress on said fragile member exceeds normal working stress.

3. In combination, a switch stand having means for operating a switch, a lock device having connections to said switch, means for operating said lock device from said switch stand, including a fragile member which will break whenever the stress on said fragile member exceeds normal working stress.

4. In combination with a switch stand, a safety lock device comprising a base, locking members on said base for holding a switch in operative position, a latch member for holding said locking members in locked position, and means whereby said latch member may be manually tripped to unlocked position

and then engaged by one of said locking members when moving to unlocked position, thereby tripping said latch member into 55 cocked position in readiness for moving into locked position.

5. In combination with a switch stand, a safety lock device comprising a base, a hollow lock block on said base and having a longitudinal chamber and a transverse first hole, a latch pivoted to said base, a cross member having a lock pin for disposition in said first hole, said cross member having an abutment to engage said latch in locked position, a lock bar in said chamber and having a second hole, said lock bar being adapted to be connected to a switch, said latch having a projection to be engaged by said cross member so that said latch will be 70 tripped against said abutment when said pin is withdrawn.

6. In combination with a switch stand, a safety lock device comprising a base, a hollow lock block on said base and having a longitudinal chamber and a transverse first hole intersecting therewith, a latch block on said base and having a second hole, a latch pivoted to said latch block, a cross bar disposed in said second hole, said cross bar having a pin for disposition in said first hole and a cross head, a lock bar disposed in said chamber and having a third hole for said pin, said lock bar being adapted to be connected to a switch, means for operating said switch and for operating said pin, including a breakable connecting rod extending to said cross head from said switch stand, said latch having a projection to be engaged by said cross bar so that said latch will be thrown 90 onto said cross head when said pin is withdrawn.

7. In combination with a switch, a first lock device having lock members for holding said switch in operative position, a second lock device for holding said switch in operative position, safety lock means on said first lock device for positively holding said lock members in locked position, and means for operating said switch.

In testimony whereof we have hereunto set our hands and seals.

PAUL HOFFMAN. [L. S.]
JAMES B. STRONG. [L. S.]
